UNITED STATES PATENT OFFICE.

EMIL J. NIELSEN, OF OAK PARK, AND OLE HORSRUD, OF CHICAGO, ILLINOIS.

CAMP STOVE.

Application filed October 4, 1926. Serial No. 139,262.

This invention relates to camp stoves generally but more particularly of a two or three burner type.

The principal objects of our invention 5 may be enumerated as follows:

First, the provision of a multiple burner camp stove wherein the burners are foldable into or out of one section of a carrying case to permit stowing in a relatively compact manner along with the other parts of 10 the stove in the case. Thus a two or even three burner stove having a master burner and one or more dependent burners and made in accordance with our invention is of 15 about the same size as single burner stoves at present available and is not as cumbersome and awkward to carry along in touring and camping.

Second the provision in a camp stove of 20 the character described of a carrying case comprising hinged sections arranged to be swung into coextensive relation to provide a stove base for supporting the burners, and also the provision in connection with the 25 case sections of a novel and simple means for holding the sections rigidly in coextensive relation and a simple and practical form of props or legs which are foldable into an out of the way position alongside 30 the case or to an extended operative position for use.

Our invention embraces still other objects and advantages to be pointed out more fully hereinafter. In the course of the following description reference is made to the 35 accompanying drawings wherein—

Figure 1 is an end view of the carrying case with all the appurtenances of the camp stove stowed therein for transportation;

40 Fig. 2 is a plan view of the case opened to show the arrangement of the burners when folded in the case and the fuel tank, grates, and other parts previous to the setting up of the stove;

45 Fig. 3 is a plan view; and

Fig. 4 is a side view of the stove set up for use, Fig. 4 having a portion of the wall of the case sections broken away to illustrate the clasp for holding the sections in rigid coextensive relation; and

50 Fig. 5 is a view similar to Fig. 3 of a modified or alternative construction showing the provision of three burners instead of two.

55 The same or similar reference numerals

are applied to corresponding parts throughout the views.

Referring for the present more particularly to Figs. 1 to 4, it will be seen that the carrying case 6 is equipped with a handle 7 so that it may be carried like a suitcase. A leaf spring latch 8 has pins 9 arranged to be received in openings in the end walls of the case sections or trays 10 and 11. The former is elsewhere referred to as the main section inasmuch as most of the parts of the stove are arranged to be stowed therein, while the other section is elsewhere referred to as a cover. The two sections are hinged together, as indicated at 12, and arranged to unfold from the closed condition shown in Fig. 1 to coextensive relation, as shown in Fig. 2, whereby to serve as a stove base as appears in Figs. 3 and 4. When so extended the sections are arranged to be held rigidly with their inner ends abutting, as appears in Fig. 4, by a clasp shown at 13. The latter operates through registering openings 14 in the abutting walls of the case sections and comprises a buckle 15 arranged to be engaged over a hook or other projection 16 provided on a strap 17 riveted to the wall of the case section 10. The buckle 15 is pivoted at 18 to a toggle link 19 which in turn is pivoted at 20 to the wall 85 of the case section 11. It is obviously a simple matter to secure the sections of the case 6 in rigid, coextensive relation the moment the case is unfolded. The buckle 15 is simply passed through the openings 14 and over the hook 16 on the strap 17 whereupon the lever 19 is forced down to the position shown in Fig. 4 where the pivot 18 is slightly past a dead center position with respect to the pivot 20.

90 A master burner 21 which has a manifold 22 leading thereto is bolted, as indicated at 23, to the bottom wall of the case section 10. When the case sections are in rigid, coextensive relation a foldable dependent or auxiliary burner 24 is arranged to be swung with its manifold 25 into the case section 11, as indicated in Fig. 3. The burner 24 in its inoperative position is stowed in the section 10 alongside the other burner 21 and in substantially the same horizontal plane therewith. The two burners are pivotally connected by their manifolds which seat on one another on finished surfaces at 26, there being a bolt 27 extending through the juncture 100 105 110

of the two manifolds coaxially with the seat 26 and provided with a coiled compression spring 28 to hold the two manifolds together in air-tight relation. The seat 26 is at such an angle that the burner 24 swings in a plane at an angle to the longitudinal axis of the extended case sections whereby to dispose the burner 24 in line with the burner 21 in substantially the middle of the case. 5 At the same time, when the burner 24 is folded in, as shown in Fig. 2, it assumes a position close to and alongside of the burner 21 so as not to take up too much room in the case. Registering notches are cut in the 10 abutting walls of the case sections at 29 to permit the swinging of the burner 24 from section 10 into section 11. Obviously, this construction permits the provision of a multiple burner camp stove without resulting in 15 an article of such size that it would be awkward and cumbersome to handle and transport. The folding of the burners in the novel manner disclosed results in such compactness that it may safely be stated that the 20 multiple burner stove provided is, when folded, no larger than single burner stoves of the designs available up to the present time. As a consequence of the bulky size of the two burner stoves at present available the camper 25 will often forego the convenience of the additional burner and procure a single burner stove in order to have the compactness which, up to the present time, has been offered only in the single burner stove. As 30 will be apparent from the foregoing, the present invention provides a double burner stove with practically the same compactness as any single burner stove now available.

The burners are supplied with fuel from 35 the usual tank 30 which, in the present case, has lugs 31 provided thereon to hook into openings provided in the end wall of the case section 10, as shown in Figs. 3 and 4. The tank has a delivery tube 32 extending therefrom over the master burner 21 and having a nipple end 33 for reception in an opening in a hollow boss 34 provided on the manifold 22. A valve 35 regulates the feeding of fuel in the usual manner. A pocket or well 36 is provided in the manifold 22. Some of the liquid fuel is discharged from the tube 32 into this pocket when starting the stove and when ignited serves to preheat the fine stream of fuel for vaporization. In the 40 course of a few minutes the stove is ready to operate to furnish the full cooking heat. A valve 37 is provided on the tank 30 so that the tank may be charged with compressed air in the usual manner. A hand pump 38, shown in Fig. 2, is provided for this purpose. The key shown at 39 fits the valve 35. These appurtenances are stored in the case when the stove is folded up, there being sufficient room alongside the burner 24, as 45 shown in Fig. 2. The tank 30, on the other

hand, is received in the space alongside the burner 21. A pair of grates 40 are stowed in the case section 10 so as to fold over the burners when the stove is folded up. The arrangement of the grates shown leaves 70 sufficient room alongside the same for the tank 30 when the case is closed. Brackets 41, provided on the end walls of the case sections 10 and 11 are arranged to receive the grates in the manner shown in Fig. 3. 75

When the burner 24 is extended for use, its flame may be extinguished or controlled by a valve 42 threading in the outer end of the burner. A pair of links 43 and 44 pivotally connected, as shown at 45, are 80 pivotally connected with the valve 42 at 46 thus permitting the folding of these links inside the case in the manner shown in Fig. 2, or the extension thereof through an opening in the end wall of the case, as shown in 85 Fig. 3. The end link 44 in adjusting the valve is swung at an angle to its companion link 43, as shown in Fig. 3, to serve as a finger piece to turn the valve.

The case sections when extended, as indicated in Figs. 3 and 4, serve as a stove base or burner support and may be suitably supported elevated off the ground by a pair of legs or props 47. These parts are in the form of bail elements generally U-shaped, as indicated in dotted lines in Fig. 1, having the arms thereof projecting through openings 48 in the walls of the case sections and having the free ends thereof out-turned to provide trunnions 49 pivotally received in openings provided in the walls of the case sections adjacent the openings 48. The free ends of the arms of the bail elements 47 are also slightly hooked, as indicated in Fig. 4, so as to lie flush alongside the case when 105 folded in, as shown in Figs. 1 and 2. The openings 48 are elongated and serve to limit the movement of the bail elements from inoperative to operative position, as will be clear in Fig. 4. The openings have their opposite ends offset so that an intermediate projecting portion 50 is provided over which the arms of the bail element have to ride in moving from one limit position to the other. In so doing the arms are flexed so that they 110 tend to spring into their limit positions when moved close to such positions and are yieldingly held against movement away from such positions. A lateral extension 51 is provided on at least one of each pair of openings 48 to facilitate entering the ends of the arms of the bail element therein when assembling 115 the stove. Obviously the construction described is extremely simple and practical for the purposes intended as the legs or props lie flush alongside the case when moved to inoperative position and may be extended quickly to an operative position for supporting the stove. When moved to either position the legs or props are not apt to require 120 125 130

any attention as the resilience of the arms thereof is sufficient to insure their staying in position.

In Fig. 5 we have shown a modified or alternative construction where, in addition to burners 21' and 24', a third burner 52 is provided on the manifold 25' of the burner 24'. The manifold 22' is offset at its inner end, as indicated at 53, to provide room for the burner 52 when the burner 24' is folded alongside the burner 21'. The two manifolds are pivotally connected in a manner similar to the connection of the manifolds 22 and 25. The fuel for the burners is supplied from the tank 30 which has its delivery tube 32 communicating with the inner end of the manifold 25' at 34'. The burner 52, similarly to the burner 21, is not arranged to be put out but operates at all times to pre-
heat the fuel for vaporization. The burners 21' and 24' are controlled by valves operated by the finger pieces 44' pivotally connected with the links 43'. This camp stove is otherwise the same in construction as the other. It will be observed that the burners, when arranged in operative position for use, are disposed in alignment with the burner 52 substantially midway between the end burners, all three burners being arranged in the middle of the case beneath the grates 40.

It is believed that the foregoing description conveys a clear understanding of the invention and of its principal features and advantages. While the constructions illustrated have been chosen for purposes of the present description as embodying the novel features herein set forth, it will be clear that many changes may be made both in construction and arrangement of parts so that our invention is not to be considered as limited to the specific constructions illustrated.

We claim:

1. In a camp stove, the combination of a carrying case comprising hinged sections arranged to be unfolded to provide a stove base, and a burner mounted in one of said sections having a second burner pivoted thereto to be swung from an inoperative position alongside the same in substantially the same horizontal plane therewith to an extended operative position in the other section in substantially the same horizontal plane.

2. In a camp stove as set forth in claim 1, the provision on the pivotal burner of a third burner adjacent the pivotal connection between the burners so as to be disposed approximately halfway between the said burners in their coextensive operative relation.

3. In a camp stove as set forth in claim 1, the provision on one of the burners of a third burner adjacent the pivotal connection between the two burners so as to be disposed

approximately halfway between the said burners in their coextensive operative relation.

4. In a camp stove as set forth in claim 1, the provision of the pivotal connection 70 between the manifolds of said burners at such an angle that the pivoted burner swings in a plane at an angle to the longitudinal axis of the two sections of the case whereby to dispose both burners on one line at approximately the middle of the case sections. 75

5. In a camp stove as set forth in claim 1, the provision of the pivotal connection between the manifolds of said burners at such an angle that the pivoted burner swings 80 in a plane at an angle to the longitudinal axis of the two sections of the case whereby to dispose both burners on one line at approximately the middle of the case sections, and a third burner on the manifold of one 85 of the other two burners arranged in the operative position of said burners to be disposed substantially midway between the first two burners and also in alignment there- 90 with.

6. In a camp stove, a carrying case comprising a main section in the form of a shallow tray having a cover section also in the form of a shallow tray, said sections being hinged together at one edge of corresponding side walls thereof so as to fold to coextended position to provide a stove base, a burner mounted in the main section, a second burner pivoted thereto and arranged to be moved from an inoperative position 100 alongside the same and substantially in the same plane therewith in the main section to an operative position in the cover section coextensive with the main burner and again in substantially the same plane therewith, 105 and means for holding said sections in rigid coextended relation to support the burners for operation. 110

7. In a camp stove comprising a carrying case arranged to serve as a burner support, means for supporting the same elevated off the ground comprising props each in the form of a generally U-shaped bail element having out-turned free ends for pivotal engagement with the sides of the case section, 115 said bail element being movable from a position alongside the case section to a position making an angle therewith, there being openings in the wall of the case section to receive the free ends of the bail element for such swinging movement, said openings being elongated and one end of said openings serving to limit the movement of said bail element to its operative position by the engagement of the arms thereof with the ends 120 of the openings, the intermediate portion of the openings being conformed to cause a flexing of the arms of the bail element whereby the bail element springs into either 125 its inoperative or its operative position from 130

an intermediate position and is held in either of the limit positions.

8. In a camp stove, a carrying case comprising a pair of hinged tray sections arranged to be unfolded to coextended relation to serve as a stove base, a master burner permanently secured within one of said tray sections, means for providing raw fuel to said burner, said burner having means for vaporizing said fuel before the entrance thereof into the manifold of said burner, and an auxiliary burner having a manifold arranged to be placed in coextended relation with the manifold of the master burner and in substantially the same horizontal plane therewith to be supplied with vaporized fuel therefrom, said auxiliary burner being also arranged to be removed from coextended operative relation for disposition alongside of and in substantially the same

horizontal plane as the master burner in the tray section with the latter when the carrying case is to be folded.

9. In a camp stove, a carrying case arranged to be unfolded to serve as a burner support, a master burner mounted in one part of the case, an auxiliary burner having a manifold arranged to be placed in coextensive relation with the manifold of the master burner and in substantially the same plane therewith or to be placed in an inoperative position alongside the main burner and again in substantially the same plane therewith, and means for supplying vaporized fuel to the manifolds of said burners. 35

In witness of the foregoing we affix our signatures.
